Primary Examiner — Barbara Fox*Assistant Examiner* — Dana K Weiland(74) *Attorney, Agent, or Firm* — Patent Capital Group(57) **CLAIM**

The ornamental design for a computing device with sensor, as shown and described.

DESCRIPTION

FIG. 1 is a perspective view illustrating a computing device with sensor according to my new design;

FIG. 2 is a front view thereof;

FIG. 3 is a back view thereof;

FIG. 4 is a side view thereof;

FIG. 5 is another side view thereof;

FIG. 6 is a top view thereof; and,

FIG. 7 is a bottom view thereof.

The broken lines represent portions of the computing device with sensor and form no part of the claimed design. The unshaded regions bounded by broken lines illustrate boundaries that form no part of the claimed design. Non-oblique line shading is meant to show contour and not surface ornamentation.
